UNITED STATES PATENT OFFICE.

JOSEPH W. WESTLAKE, OF MARYSVILLE, OHIO.

FENCE-POST.

No. 823,655.

Specification of Letters Patent.

Patented June 19, 1906.

Application filed October 6, 1905. Serial No. 281,692.

To all whom it may concern:

Be it known that I, JOSEPH W. WESTLAKE, a citizen of the United States, residing at Marysville, in the county of Union and State of Ohio, have invented a new and useful Fence-Post, of which the following is a specification.

This invention relates to fence-posts, and has for an object to provide a post embodying new and improved features of economy, convenience, durability, and utility.

A further object of the invention is to provide a post which may be readily and easily placed in position and as easily removed from the position for change of location.

A further object of the invention is to provide a concrete post having a horizontal base-section, a vertical section joined at its lower end to one end of the base-section, and an oblique base-section with cross-heads at the ends of the horizontal section, and all-molded integral and with any approved form of reinforcing-pieces and fastening devices embedded in the concrete structure.

With these and other objects in view the present invention consists in the combination and arrangement of parts, as will be hereinafter fully described, shown in the accompanying drawings, and particularly pointed out in the appended claims, it being understood that changes in the form, proportion, size, and minor details may be made without departing from the spirit or sacrificing any of the advantages of this invention.

In the drawings, Figure 1 is a perspective view of the improved post with a fragment broken away to show the reinforcing. Fig. 2 is a fragmentary perspective view of a modified form of post used in connection with the post shown at Fig. 1 to form a corner.

Like characters of reference indicate corresponding parts in all of the figures of the drawings.

In its preferred embodiment the improved fence-post forming the subject-matter of this application is composed of concrete or like material molded to produce a vertical section 10, joined at its lower end to the horizontal section 11 and with the extremities 50 united by an obliquely-disposed brace-section 12. At opposite ends the horizontal section is provided with cross-heads 13 and 14, the latter being perpendicular to the vertical section 10.

While being molded any approved fasteners, as 15 and 16, may be embedded in the

structure, and a reinforcing member, as 17, may likewise be embedded, the reinforcing and the fastening 16 being preferably, though not necessarily, integral, as shown. The 60 cross-heads 13 and 14 may likewise be reinforced by the members 18 and 19, respectively, extending transversely of the post.

The fasteners here shown are adapted to serve as studs to form one member of a gate-hinge, whereby the post is adapted for use as a gate-post; but it is to be understood that other forms of fasteners may be used or the fasteners shown used for different purposes, as for attaching wires or boards. The fastener 16 is intended to connect the post to a dead-man or other form of anchorage when found necessary or desirable. Attention is called to the fact that the reinforcing member 17 is in the form of a triangular-shaped 75 loop the reduced end of which forms a support for the reinforcing members 18, while the enlarged end thereof forms a support for the members 19, the end of the wire at the enlarged end of the loop being coiled or otherwise twisted around the horizontal leg of the loop at a point adjacent the member 16, as shown. The post is "set" by embedding in the earth to about the top of the horizontal section, the dead-man of course when used 85 being embedded deeper. To remove the post, the wire or other connection from the dead-man is disconnected from the fastener 16 and the post lifted from its socket in the earth. It will not generally be necessary to 90 anchor the post, as owing to its weight and construction it will stand firmly, if embedded in a reasonably heavy soil; but provision is made for anchorage, when desired.

In forming a corner two posts are used, and the base 14 of one is found to contact with the other and hold the post at a distance. To overcome this feature, a modified form is used for one post, as in Fig. 2, wherein the cross-head shown at 14' extends upon one 100 side only of the vertical and horizontal sections. It will be obvious that the fasteners 15 or their equivalents may be so embedded as to protrude from a side of the vertical, where that position would be more convenient and efficient.

Having thus described the invention, what is claimed is—

1. A fence-post comprising an elongated base, provided with oppositely-disposed cross-heads, a standard secured to the base at a point intermediate one of the cross

heads, and a diagonal brace spaced from the base and connecting the free end of the standard and the opposite cross-head.

2. A plastic fence-post comprising a horizontally-disposed base having a cross-head at each end thereof and extending laterally beyond the general longitudinal plane of the base, a standard secured to the base at a point intermediate one of the cross-heads; and an integral brace spaced from the base and connecting the free end of the standard and the intermediate portion of the opposite cross-head.

3. A plastic fence-post comprising a horizontally-disposed base having integral cross-heads at opposite ends thereof and extending laterally beyond the general longitudinal plane of the base, an integral standard extending vertically from the base at a point intermediate one of the cross-heads, an integral diagonally-disposed brace spaced from the base and connecting the free end of the standard and intermediate portion of the opposite cross-head, a continuous reinforcing-bar embedded in the base, standard and diagonal brace, and bars extending longitudi-

nally of the cross-heads and engaging the reinforcing-bar.

4. A plastic fence-post comprising a horizontally-disposed base having integral cross-heads at opposite ends thereof and extending laterally beyond the general longitudinal plane of the base, a standard secured to the base at a point intermediate one of the cross-heads, a diagonal brace spaced from the base and connecting the free end of the standard and the intermediate portion of the opposite cross-head, a triangular-shaped reinforcing-bar embedded in the base, standard and brace and having one end thereof extending beyond the adjacent cross-head to form an anchor-engaging hook, and bars extending longitudinally of the cross-heads and engaging the reinforcing-bar.

In testimony that I claim the foregoing as my own I have hereto affixed my signature in the presence of two witnesses.

JOSEPH W. WESTLAKE.
